WILLIAM T. B. McDONALD, OF GRANBY, QUEBEC, CANADA, ASSIGNOR TO MACDONALD CAR BUFFER LIMITED, OF MONTREAL, QUEBEC, CANADA, A CORPORATION.

MEANS FOR STOPPING TRAINS.

1,084,463.

Specification of Letters Patent. Patented Jan. 13, 1914.

Application filed September 12, 1913. Serial No. 789,524.

To all whom it may concern:

Be it known that I, WILLIAM T. B. McDONALD, of Granby, in the Province of Quebec, Dominion of Canada, a subject of the

5 King of Great Britain, have invented certain new and useful Improvements in Means for Stopping Trains; and I do hereby declare that the following is a full, clear, and exact description of the same.

10 My invention relates particularly to the buffers or bumping posts commonly used at railway terminals for preventing runaway trains or trains the speed of which is not checked in time owing to the lack of judgment, or for other reasons, from being wrecked or wrecking the station or doing other damage beyond the established end of the line.

The object of this invention is to provide 20 a buffer containing elastic and comparatively inelastic fluids and valvular piston means actuated by the inertia of the train being stopped to cause the resistance of the elastic fluid to first come into effect and then 25 the resistance of the inelastic, the valvular piston being adapted to automatically reduce the resistance offered by the inelastic fluid, and, furthermore, to automatically vary this reduction in order to impart to 30 the buffer maximum yielding resistance before it begins to slide thus materially increasing the effectiveness of the buffer which will absorb the inertia of the moving train by converting the weight of the forward 35 part of the train into frictional resistance and supplementing the frictional resistance by a resistance increasing progressively until a rigid stop is presented.

A further object of the invention is to improve 40 the general construction of this type of buffer.

This invention may be said briefly to consist of a buffer mounted slidably on the rails at a terminal and comprising in combination with a member mounted slidably upon the rails of a closed cylinder containing a piston and adapted to be actuated by the inertia of the moving train and a particular structural feature whereby a comparatively inelastic fluid such as oil located in one end of the cylinder is caused to be

discharged therefrom to the opposite side of the piston when the latter nears the end of the cylinder; such structural feature preferably consisting of grooves in the bottom 55 of the cylinder near each end thereof and disposed parallel to the axis and in order to secure a discharge approximately increasing in proportion to the compressive force exerted on the oil the grooves are made to increase in capacity toward the ends of the cylinder.

Another feature of the invention consists of the combination with a rigidly secured terminal stop, of a particular construction 65 of a pair of elongated friction members bearing slidably on the rails and adapted to have the forward end of a moving train run thereon; and the invention further consists of the combination, particular arrangement and specific construction of parts hereinafter described and pointed out in the claims.

For a full comprehension, however, of this invention reference must be had to the 75 accompanying drawings forming a part of this specification in which similar reference characters indicate the same parts, and wherein:

Figure 1 is a side elevation of means for 80 stopping trains constructed according to my invention; Fig. 2 is a detail front elevation of the buffer proper; Fig. 3 is a plan view; Fig. 4 is a rear elevation; Fig. 5 is a detail sectional view taken on line A A Fig. 3 85 and drawn to an enlarged scale; Fig. 6 is a detail sectional view taken on line B B Fig. 3 and drawn to an enlarged scale; Fig. 7 is a detail sectional view taken on line C C Fig. 3 and drawn to an enlarged scale; and 90 Fig. 8 is a detail side elevation illustrating the members of one of the joints separated.

A pair of rails at a terminal of a railway are indicated at *b* and a pair of depressed rails approximately one hundred feet long 95 are indicated at *50*. These latter have their flanges embedded in concrete *c* for a distance of about fifteen feet from their terminal ends, and a pair of heavy rail sections *d* are set vertically in the concrete in positions 100 with rails *50* abutting against them, the top ends thereof projecting a short distance

above the rails 50. A pair of elongated shoes rest slidably upon the depressed rails and consist preferably of cast steel or forged sections 51 of channel cross-section having their longitudinal middle of substantially rail-head form in cross-section, and sections 52 having their main length of irregular oblong cross-section, one end 53 being preferably of similar cross-section to the sections 51 excepting that the head portion is cut away as at 54 to form a seat for a correspondingly cut away end portion 55 of the sections 51, such sections 51 and 52 being united through these overlapping parts by keys 56 and rivets 57. The shoes thus formed are united by a cross bar 58 bolted thereto through lugs 59 cast or forged integral with the sections 51 of the shoe and the end portions of sections 52. These shoes are preferably about sixty feet in length and straddle the rail heads with a snug sliding fit. The depressed rails are united to the rails b they abut by means of combination fish plates and auxiliary-rails 60 approximately twelve feet long and bolted to the rails b and 50. These auxiliary rails are shaped to present flat portions 61 and 62 adapted to lie against the webs of the normal depressed rail 50 and rail b , the portion above the flat part 61 being shaped to extend around the head of rail 50 as at 63 and upwardly to present a guiding wall 64 having a flat side 65 engaged by the portion 52 of the shoe. There are a pair of these combination fish-plates and auxiliary rails secured to both sides of each rail. A casting comprising a main cylinder s and a pair of cylinders 13 of smaller bore (to be presently further alluded to) and a pair of heavy webs k with flanged feet 67, is secured rigidly through these feet to the shoes, preferably by bolts m , and the ends of the shoes are bent over the ends of the webs and secured thereto as at o .

The cylinder is hermetically sealed and contains a piston t and a comparatively small quantity of oil and the opposite ends thereof are provided with vacuum and compression safety valves 2 and 3 respectively.

A plunger bar 4 projects from the front of the piston through a stuffing box 5 in the front cylinder-head and has a buffer head 6 formed or secured rigidly thereon and provided with a transverse flange 4^a at its top.

In order to yieldingly retain the piston and with it the buffer normally in its extreme forward position, a pair of lugs 7 are carried by the buffer head and extend laterally therefrom, such lugs having connected thereto a pair of plungers 8 the inner ends of which have flanged heads 10 upon which bear helical springs 12 located in the cylinders 13 above mentioned. This cylinder is charged with a quantity of oil equal to about one-fifth more or less of the capacity of one end and in order to charge it the piston is first located at about mid-stroke and the oil is poured into one end. Each end of the cylinder is formed with a duct extending from the ends toward the center for a distance slightly greater than the length of the piston and in order to cause the fluid from this duct to be reduced in proportion to the proximity of the piston to the cylinder end, this duct preferably consists of three grooves s' , s^2 , and s^3 extending parallel to the axis and united by a transverse groove or header s^4 at the cylinder end, the grooves being of different lengths. This sliding buffer, constituted by the shoes, webs, cylinder and the parts contained within and carried by the cylinder, and buffer head, is preferably located about forty feet from the rigid stops d , and the auxiliary rails are about twelve feet in length. The appliance is held semi-rigidly in that position by a pair of clamps 20 clamped to the rails at the terminal end of the buffer and clamps 21 clamping the shoes and forward ends of the webs to the rails; while a platform 25 extends over the stops d and the space between them and the sliding buffer. The flange 4^a has for its function to prevent the locomotive from climbing over the buffer when the coupler strikes the buffer block.

Operation: Under normal conditions the appliance is held by the clamps 20. When a train exceeds the point at which it should stop it will run onto the shoes, and, if its excessive travel is sufficient but the inertia comparatively low, the train may be stopped by the resistance offered by the air compressed in the forward end of the cylinder augmented by the vacuum created in the rear end of the cylinder. If, however, the inertia is sufficiently high, the train after running onto the shoes and into contact with the buffer head will drive the piston to the forward end of the cylinder and force the oil through first three grooves then two grooves s and s' and finally by groove s' alone as the inner ends of these grooves are uncovered by the piston and communication is effected between both sides of the latter. The passage of this oil is retarded by the progressively reducing capacity of the grooves thus offering a yielding resistance varying as the piston advances. Assuming that the inertia continues sufficiently high it will start the entire appliance and the clamps 20 and 21 with it without any perceptible shock, until the friction of the shoes sliding upon the rails while bearing the load of the locomotive and whatever portion of the train runs upon the shoes, stops the train. Under such condition the telescopic connection, which is preferably about twelve feet in length, is extended, a drop in the level of

the rail tread between the ends of the displaced shoes and rails *b* being prevented by the auxiliary rails 60. During this displacement of the buffer, the platform, if one is used, will give way. Trains of approximately five hundred tons and crossing the terminal at a speed of, say, thirty miles an hour, will be stopped within twelve feet, although trains of greater inertia may require 10 the forty feet allowed, but heavier trains or trains crossing the terminal at a higher speed may possess sufficient inertia to cause the buffer to reach the rigid stops *d* before being arrested. The fact that the ends of 15 the rails *b* and the vertical rails *d* are embedded in a solid foundation of concrete or cement prevents creeping of the rails, and thus supplements the resistance of the air compressed and vacuum created and oil 20 located in the buffering cylinder and the friction of the shoes on the rails sufficiently to absorb the inertia of and bring to a stop practically the heaviest train running over the terminal at maximum speed without 25 actually wrecking it.

The advantageous effect obtained with the use of oil is that a longer and higher resistance is provided owing to the fact that when the piston commences to compress the 30 air between it and the end of the cylinder it also reduces the space within which the oil is confined causing the oil to rise and compress the air thus causing compression of the air from two sides instead of one. The 35 ducts serving to release the oil when the maximum resistance is reached afford the means for maintaining sufficient space to accommodate the air cushion.

What I claim is as follows:—

40 1. A railway train stopping appliance comprising a pair of shoes supported slidably upon the rails at a railway terminal, and a buffer mounted upon the shoes in position to receive the impact of a train running upon the shoes, such buffer containing 45 a hermetically sealed cylinder containing a relatively small proportion of inelastic fluid, and means located at the ends of the cylinder whereby the said inelastic fluid is caused to pass from one to the other side of 50 the piston is utilized in the absorption of the inertia of the moving train.

2. The railway train stopping appliance having a pair of webs mounted rigidly upon 55 the shoes, a hermetically sealed cylinder rigidly secured upon the webs, a piston in the cylinder such cylinder having at its ends wall ducts of a length less than the cylinder and greater than the piston, a bar secured 60 to the piston and projecting through one end of the cylinder and having a buffering head at its outer end.

3. The railway train stopping appliance having a pair of webs mounted rigidly upon

the shoes, a hermetically sealed cylinder 65 rigidly secured upon the webs, a piston in the cylinder such cylinder having at its ends wall ducts of a length less than the cylinder and greater than the piston each of the said ducts consisting of a plurality of grooves of 70 varying length, a bar secured to the piston and projecting through one end of the cylinder and having a buffering head at its outer end.

4. The railway train stopping appliance 75 having a pair of webs mounted rigidly upon the shoes, a hermetically sealed cylinder rigidly secured upon the webs, a piston in the cylinder such cylinder having at its ends wall ducts of a length less than the cylinder 80 and greater than the piston each of the said ducts consisting of a plurality of grooves of varying length and a transverse groove uniting the said plurality of grooves, a bar secured to the piston and projecting through 85 one end of the cylinder and having a buffering head at its outer end.

5. A railway train stopping appliance comprising in combination with normal rails, and depressed rails, of a pair of shoes resting 90 slidably upon the depressed rail-portions and a buffer mounted rigidly upon the shoes.

6. A railway train stopping appliance comprising in combination with normal rails 95 and depressed rails, of a pair of shoes resting slidably upon the depressed rail-portions and approximately equal in thickness to the depth of the depression and a buffer mounted rigidly upon the holes. 100

7. A railway train stopping appliance comprising in combination with normal rails and depressed rails, of a pair of shoes resting slidably upon the depressed rail-portion such shoes being of channel cross-section and a buffer mounted rigidly upon the 105 shoes.

8. A railway train stopping appliance comprising in combination with normal rails and depressed rails, of a pair of shoes resting 110 slidably upon the depressed rail-portion such shoes being of channel cross-section with projecting portions lying slidably upon the tops of the depressed rail heads; combination fish-plates and auxiliary rails secured to the normal and depressed rails and overlapping the slidable shoe projections and a buffer mounted rigidly upon the shoes. 115

9. A railway train stopping appliance comprising in combination with railway 120 rails, of a pair of elongated shoes resting slidably upon the rails and carrying a buffer consisting of a main closed cylinder and a pair of cylinders at the sides thereof, a piston in the main cylinder, a bar secured at 125 one end to the piston and projecting through one closed end of the main cylinder, a buffering head upon the outer end of the bar and hav-

ing a pair of laterally extending lugs, rods secured at their outer ends to the lugs and projecting into the said pair of side cylinders, and springs within the said last mentioned 5 cylinders and resisting the movement of the rods thereinto for the purpose of returning the buffing head to normal position.

In testimony whereof I have signed my name to this specification in the presence of two witnesses.

WILLIAM T. B. McDONALD.
